UNITED STATES PATENT OFFICE.

CHARLES E. PAYNE, OF NEW YORK, N. Y.

DIGGING APPARATUS.

Application filed October 18, 1926. Serial No. 142,311.

The present invention relates to digging or excavating apparatus or tools employed for digging post-holes and the like. The invention consists of certain improvements in apparatus or tools of this kind and the chief object of the invention is to provide an efficient tool which is simple in construction and operation and which may be used either for manual or power operation.

10 The improved tool in one form is in the nature of an auger having a bucket at each side and these buckets are provided at their lower and closed end with lips or bits so arranged that the earth displaced thereby is taken into the buckets and when the tool is withdrawn from the hole, the buckets can be readily emptied. Provision is made in one form of the invention for dumping these buckets which in this case are pivoted 15 and have associated therewith means for tilting the buckets to discharge the contents therefrom.

15 The improved tool has a shank carrying a head and said shank may be extended to allow holes or excavations of varying depth 20 to be dug and which shank may be operated by hand or power as desired. The head of the tool consists of a supporting plate or member secured to the shank and at each side 25 of said member, a bucket is mounted. In one form of the invention, the buckets are secured against any independent movement. This form is useful for digging comparatively small and shallow holes and this tool 30 must be bodily tilted at various angles to empty the buckets. In another and preferred form, the buckets are pivotally mounted on the supporting member and means, comprising an operating lever, a pair 35 of eccentrics and a connecting link or links, are provided for turning the buckets on their pivots so as to empty them.

It frequently occurs that holes or other excavations of comparatively great depth 40 are required to be dug and in a sandy or loose earth and so to avoid caving in of the sides of the excavation, a lining, in sections 45 is dropped into the hole during the digging operation. To accomplish the desired results, it is proposed to employ a follower or ring which is loosely engaged by the head or auger part of the tool. This ring follows 50 the auger and clears the way for the tubular lining sections which are dropped into the hole around the tool as it advances into the earth. The tool must be withdrawn from

the hole to empty the buckets and with a power driven digger, the buckets may be automatically operated.

In order that the invention may be more clearly understood, an embodiment of the same will be hereinafter fully described and illustrated in the accompanying drawings wherein—

Figure 1 is a side elevation of the improved tool in the position for operation;

Figure 2 is a plan view of the ring or follower employed in conjunction with the improved tool;

Figure 3 is a side elevation of said ring or follower;

Figure 4 is a side elevation of the improved tool partly in section, and

Figure 5 is a side elevation of the improved tool partly in section showing the side of the tool opposite to the side shown in Figure 4.

Figure 6 is a top plan view of the improved tool, and Figure 7 is a cross sectional view of the improved tool.

Referring to the said drawings, the tool shown therein is composed of a head 1 in the form of a plate having secured thereto the operating shank 2 which latter is shown as being broken away. Obviously the shank 85 may be of any length according to the depth of the hole to be dug or if desired said shank may be composed of sections with means for joining the same together to obtain a shank of the required length. At 90 each side of said plate 1, buckets are mounted on a common pivot 3 and said buckets are respectively designated by the numerals 4 and 5. These buckets turn on the pivot 3 so as to assume opposite angular positions wherein 95 the contents of the buckets may be dumped therefrom. It will be noted during the digging operation, the buckets are in alignment with the shank, as shown in Figure 1.

Means are provided for operating the buckets and these means comprise a pair of eccentrics 6 and 7 which are mounted on a common pivot 8 and said means also includes an operating lever 9 which is secured to the eccentric 6. The eccentrics 6 and 7 are 100 fixedly mounted on the pivot 8 in such a manner that operation of the lever 9 will effect a partial turning of both eccentrics with a cam-like movement. Transmission means are employed to connect the bucket 4 with the eccentric 6 and such means comprises the slotted link 10 which is pivoted at 11 on the

bucket 4, the slot 12 of the link 10 engaging the pin 13 mounted on the eccentric 6. It will be understood that the operation of the lever in a downward movement will tilt the bucket 4 into the angular position shown in Figure 4 and when the lever is in the raised position, up against the stop 14, the bucket 4 is held in its closed position for operation.

The companion bucket 5, on the other side 10 of the head, is operated directly by the eccentric 7, as shown in Figure 5. The turning of both of the eccentrics in the direction of the indicating arrow, causes the eccentric 7 to bear against the pin 15 of the bucket 5 15 and thus cause this bucket to assume the angular or dumping position. When the eccentrics are turned in the reverse direction, the eccentric 7 bears against the sides of the bucket to close the same.

20 It will be seen that in the above arrangement, the buckets are operated directly and indirectly by the operating lever and it will be understood that this lever may be operated by hand or automatically, depending 25 whether or not the tool is operated manually or by power.

Both of the buckets are provided with removable lips or bits 16 in the form of plates which are bolted to the bottom of the buckets 30 and which bits are easily replaced and may be composed of tempered steel and formed to meet the different requirements which must be met when the earth is hard and rocky, or soft and sandy.

35 In cases where a comparatively small and shallow hole is to be dug in fairly hard soil the tool as described will alone answer the purpose, but in such cases where a deeper hole or excavation is to be dug, or if the hole 40 is to be dug in sandy soil, which is apt to cave in, the hole is reinforced with a lining as shown in Figure 1. In this case, the follower or ring 17 is employed. This ring may be composed of a cheaper grade of 45 metal and is not required to be machined, therefore, a rough casting may be used. This ring is located around the head of the tool and is loosely engaged thereby by means of lugs 18 so that said ring 17 will turn with 50 the tool when the latter is turned in the direction indicated by the arrows, and when the tool is turned in the reverse direction, said lugs are disengaged. Serrations 19 are formed on the lower edge of the ring 17 so 55 that it will assist the bits 16 in cutting its way into the earth. The ring 17 remains in the hole and forms part of the lining. Additional lining sections 20 are dropped into the hole around the tool as the same advances down into the earth and by this 60 means a retaining wall is provided for the hole.

In the operation of the improved tool, the buckets are held in the position of alignment

with the shank during the digging operation 65 and the earth which is displaced by the bits, is received in the buckets and when the latter are full, the tool is lifted out of the hole and the buckets are then brought to their angular or dumping position by operation of 70 the operating lever. To simplify the construction, the buckets are brought back to their aligned position by operation of the lever but obviously a spring or springs may be employed to effect the self-return of the 75 buckets to their aligned position.

Various modifications may be made in the construction and arrangement of the improved tool hereinbefore described and various ways of employing the same may be 80 adopted therefore it is to be understood that any modification coming fairly within the terms of the appended claims shall be covered thereby.

I claim—

1. An excavating tool having a head with a shank extending therefrom, a pair of buckets pivotally mounted on opposite sides of said head so as to permit a tilting movement of said buckets parallel to each other and means for turning said buckets on their pivot whereby the contents of said buckets are discharged.

2. An excavating tool having a head with a shank extending therefrom, a pair of buckets pivotally mounted on opposite sides of said head and means comprising an operating lever, a pair of eccentrics, and a link connection whereby said buckets are simultaneously tilted to discharge contents 100 thereof.

3. An excavating tool having a head with a shank extending therefrom, a pair of buckets pivotally mounted on opposite sides of said head and means comprising an operating lever and a pair of eccentrics whereby said buckets are simultaneously operated, one of said eccentrics operating one bucket directly and the other eccentric operating the other bucket indirectly through the medium of a connecting link.

4. An excavating apparatus composed of a tool having a head with a shank extending therefrom, said head carrying a pair of buckets pivotally mounted thereon so as to permit a tilting movement of the buckets in a direction parallel to each other, means for operating said buckets, a follower or ring encircling said head and having inwardly extending lugs loosely engaged by said head so as to rotate therewith in one direction of movement and said follower or ring serving in conjunction with added sections to form a retaining wall for the excavation.

Signed at New York, in the county of Bronx and in the State of New York this 13th day of October, 1926.

CHARLES E. PAYNE.
